UNITED STATES PATENT OFFICE.

OSCAR V. HOWELL, OF NEMAHIA, NEBRASKA.

DUMPING-SCRAPER.

1,241,383.

Specification of Letters Patent. Patented Sept. 25, 1917.

Application filed February 3, 1917. Serial No. 146,437.

To all whom it may concern:

Be it known that I, OSCAR V. HOWELL, a citizen of the United States, residing at Nemaha, in the county of Nemaha and State 5 of Nebraska, have invented certain new and useful Improvements in Dumping-Scrapers; and I do hereby declare the following to be a full, clear, and exact description of the invention, such as will enable others skilled 10 in the art to which it appertains to make and use the same.

This invention relates to a dump scraper, and the primary object of the invention is to provide a scraper which will dump itself, 15 after it has been raised a certain distance by the operator thereof through the medium of the handles.

Another object of this invention is to provide a dump scraper structure including 20 an ordinary scraper bottom which has a clevis pivotally connected to its forward end, to which clevis is connected a plurality of upstanding eyes and to provide handles, the forward ends of which are pivotally 25 connected to the upstanding eyes.

A still further object of this invention is to provide resilient rods or arms which are carried by the sides of the handles and have their ends angled and extending 30 through the handles for insertion into slots formed in the sides of the scraper bottom for causing the handles and the scraper bottom to move in unison for a limited distance, after which the ends of the resilient 35 arms move out of the slots and allow the scraper bottom to dump or move forwardly to a dumping position, independently of the movement of the handles.

With the foregoing and other objects in 40 view, this invention consists in certain novel features of construction, combination and arrangement of parts as will be hereinafter more fully described, illustrated in the accompanying drawings, and claimed.

In describing the invention in detail, reference will be had to the accompanying drawings, wherein like characters designate like and corresponding parts throughout the several views and in which,

50 Figure 1 is a side elevation of the improved dump scraper.

Fig. 2 is a top plan view of the scraper showing parts in section, and

55 Fig. 3 is a side elevation of the scraper showing the same in a dumped position.

Referring more particularly to the draw-

ings, 1 designates the scraper bottom as an entirety, which has a horizontal bottom having a rear end 3 formed thereon and extending perpendicularly therefrom, and upstanding sides 4, the forward edges of which curve downwardly as shown at 5 so as to provide a scraper for scooping or scraping up dirt or the like which is to be transported from one place to another. The 65 scraper bottom 1 has a pair of metallic straps 6 connected thereto, to which straps are pivotally connected the legs 7 of a clevis 8, as clearly shown at 9. The clevis 8 is substantially U-shaped and it has a substantially 70 V-shaped hook 10 connected to the center of the bight portion thereof which is adapted for facilitating the connection of any type of draft means to the dump 75 scraper.

The legs 7 of the clevis 8 are flat and lie in substantially a horizontal plane and they have ears 12 attached thereto short distances forwardly of the pivotal points 9 of the legs of the clevis as clearly shown in the 80 drawings. The forward ends of bars 13 are turned down and pivotally connected to the upstanding ears 12 as shown at 14. The bars 13 form the sides or legs of a substantially 85 U-shaped bar 15 to which is connected handles 16. A suitable brace 17 is connected to the handles 16 and to the bight portion of the U-shaped clevis, as clearly shown in Fig. 2 of the drawings. The side bars or legs 13 of the U-shaped member 15 have resilient 90 rods or wires connected thereto in any suitable manner as shown at 19. The forward ends of the resilient rods 18 are connected to the bars 13, while the rear ends 20 of these resilient rods are bent at right angles 95 to the bars 13 and extend through openings 21 formed in the bars. The angled ends 20 of the resilient rods 19 extend into slots 22 which are formed in the sides 4 of the scraper bottom 1 and form means for connecting the handles 16 and the U-shaped bar 15 to the scraper bottom. When the 100 scraper is being loaded, it is positioned, as shown in Fig. 1 of the drawings, and after it has been loaded and it is desired to dump the scraper, the handles 16 are moved upwardly which moves the scraper upwardly therewith into the position shown in dotted lines in Fig. 3 of the drawings, or until the 105 handle 16 and the legs 13 assume substantially a vertical position at which times the angled ends 20 will have traveled out of the

75

95

100

105

110

ends of the slot 22 which slots extend beyond the ends of the sides 4 of the scraper bottom as clearly shown in Fig. 2 of the drawings. This disconnects the scraper bottom 1 and the U-shaped member 15 and allows the scraper bottom to fall forwardly into the position illustrated in solid lines in Fig. 3 of the drawings, which allows it to empty or dump its contents. The rear end 10 of the scraper bottom has a pair of spurs 24 carried thereby which extend into the ground when the scraper is in a dumping position, so that during the forward travel of the scraper after it has been dumped, the 15 scraper will be prevented from sliding along the ground and consequently the pull of the draft animal will be administered to the scraper bottom in such a way as to cause the front edge thereof to move downwardly, 20 consequently moving the rear end 3 upwardly and righting the scraper bottom 1. During the righting movement of the scraper bottom 1, the angled end 20 will pass into the slots 22 and the scraper will 25 be ready for the operation previously described.

In reducing the invention to practice certain minor features of construction, combination and arrangement of parts may necessitate alterations to which the patentee is entitled provided such alterations are comprehended within the scope of what is claimed.

What is claimed is:

35 1. In a scraper structure, the combination, of a scraper bottom, a clevis pivotally connected to the sides of said bottom and extending forwardly therefrom, a substantially U-shaped bar, the forward ends of 40 the legs of said bar being pivotally connected to said clevis, handles attached to the rear ends of the legs of said bar, the sides of said scraper bottom being provided with longitudinally extending slots, resilient arms 45 carried by the legs of the U-shaped member and having their rear ends bent and extending through the legs and into said slots for connecting said handles and U-shaped

member to said scraper bottom, the legs of said U-shaped member being connected to 50 said clevis eccentrically of the pivot connected between the clevis and the scraper bottom so that the angle ends of said resilient rods will move out of said slots for disconnecting said scraper bottom and said handles when the scraper bottom reaches substantially a perpendicular position during its dumping movement.

2. In a scraper structure, the combination, of a scraper bottom, a clevis pivotally connected to the sides of said bottom and extending forwardly therefrom, a substantially U-shaped bar, the forward ends of the legs of said bar being pivotally connected to said clevis, handles attached to the rear 60 ends of the legs of said bar, the sides of said scraper bottom being provided with longitudinally extending slots, resilient arms carried by the legs of the U-shaped member and having their rear ends bent and extending through the legs and into said slots for connecting said handles and U-shaped member to said scraper bottom, the legs of said U-shaped member being connected to said clevis eccentrically of the pivot connected 70 between the clevis and the scraper bottom so that the angle ends of said resilient rods will move out of said slots for disconnecting said scraper bottom and said handles when the scraper bottom reaches substantially 75 a perpendicular position during its dumping movement, a pair of spurs attached to and projecting beyond the upper edge of the rear side of said scraper bottom and adapted for embedding in the ground when the scraper bottom is in a dumped position 80 for causing the scraper bottom to right itself upon forward pulling movement thereupon.

In testimony whereof I affix my signature 90 in presence of two witnesses.

OSCAR V. HOWELL.
